UNITED STATES PATENT OFFICE.

BERNARD H. SKELLY, OF BRIDGEPORT, CONNECTICUT.

FORCE-FEED LUBRICATOR.

1,317,901.

Specification of Letters Patent.

Patented Oct. 7, 1919.

Application filed November 14, 1918. Serial No. 262,432.

To all whom it may concern:

Be it known that I, BERNARD H. SKELLY, a citizen of the United States, residing at the city of Bridgeport, in the county of Fairfield and State of Connecticut, have invented certain new and useful Improvements in Force-Feed Lubricators; and I do declare the following to be a full, clear, and exact description of the invention, such as will 10 enable others skilled in the art to which it appertains to make and use the same.

This invention relates to certain new and useful improvements in a lubricator of the type disclosed and claimed in my Patent No. 15 1,268,869, issued June 18, 1918.

In my former construction the operation effected simultaneous lubrication of all the bearings to which it was connected, but in a mechanism, such as the automobile, there are 20 certain bearings which require lubrication more frequently than others and for this reason it is preferable to have a selective operation for the lubricator.

The principal object, therefore, is to provide 25 an improved lubricator having a plurality of independent sets of pumps operable in a selective manner by independent instrumentalities so that different bearings may be oiled at varying intervals.

The invention further resides in a 30 plurality of separate sets of pump cylinders each set having independent aligned spring retracted plungers operable therein, each series of plungers being driven by a compound cam member whose cam parts are 35 relatively offset and having the same axis of revolution so that the upward pressure of half of the plungers against the cam element will be counteracted by the pressure 40 of the remaining plungers against such element.

Further, the invention resides in the salient features of construction and the arrangements and combinations of parts hereinafter described and claimed whereby a 45 great saving in the material and labor of manufacture will be effected.

In the drawings;

Figure 1 is a vertical longitudinal section 50 through the improved lubricator;

Fig. 2 is a transverse section thereof on line 2-2 of Fig. 1.

Fig. 3 is a top plan view of the reservoir and the contained cylinder blocks, and

Fig. 4 is a detailed perspective of one of 55 the cams.

Referring more particularly to the drawings, the casing or reservoir 1 is equipped with a cover plate 2 by the removal of which access may be obtained to the interior working mechanism of the lubricator. 60

A pair of cylinder blocks 3 is preferably formed integral with the opposite side walls of the reservoir and is spaced off the bottom to provide ample passage therebeneath for proper circulation of the lubricant to the inlets 4 of the pump cylinders 5. The cylinders are bored vertically through the top faces of the cylinder blocks and have their bottoms counterbored to form valve seats 70 for the valves 6 and also to provide said inlets 4. Laterally and outwardly from each cylinder leads an outlet port 7 adapted to receive a valved nipple (not shown) for connection with the respective bearings of 75 the mechanism to be lubricated.

Plungers 8 are vertically operable in the cylinders and are normally held in elevated position by the encircling coiled springs 9 interposed between the heads 10 of the 80 plungers and seats 11 on the upper faces of the cylinder blocks.

Arranged above each block and its plungers is a cam shaft 12 having its ends journaled in the end walls of the reservoir and 85 extended to provide wrench holds 13. A pair of cams 14 and 15 are carried on each shaft, said cams being longitudinally and eccentrically bored to receive the shaft and are fixed theron by the transverse key pins 90 16. The cams are relatively at an angle of approximately 180° and one cam 14 is preferably formed with a concave seat or recess 17 in an end for receiving the adjacent end of cam 15, as depicted in Figs. 1 and 95 4. This interlock between the ends of the cams provides a positive connection and relieves the key pins 16 from some of the strain they would otherwise be subjected to, but, of course, these cams 14, 15, may be 100 formed integral, if desired.

As shown in the drawing there are two independently operable sets of aligned plungers 8, which are always held against their respective cams by the coiled expansion 105 springs. Half of the plungers of a set thus tend to lift or rotate the contacting cam in one direction, as indicated by cam 15 in Fig. 1, but this tendency is overcome or resisted by the action of the companion plungers in 110 the set which tend to rotate the adjoining portion of the cam in the opposite direction.

- This counteraction is quite essential in this type of lubricator, for the reason that the wrench is removed and replaced frequently during a complete cycle, and, therefore, 5 should a single cam uniformly positioned at one angle be employed the action would be common to all plungers of a set, and every time the wrench was removed from its hold the cam would be forced back and no 10 pumping action of the plungers would result. This improved arrangement, therefore, renders the operation uniform and easy by reason of the fact that one part of the cam and its under set of plungers would be 15 lowering while the companion part of said cam and its set of plungers would be rising. The cylinder blocks are here depicted integral with the reservoir but obviously they may be separate therefrom. Various other 20 changes may also be resorted to in carrying out the invention, as defined by the appended claims, into actual practice.
- What is claimed is:
1. A lubricator comprising a reservoir, a cylinder block structure therein having alined cylinder bores provided with inlet and outlet ports, spring retracted plungers operable in the cylinders, and relatively immovable counterbalanced cams for actuating the plungers, said cams having the same axis of revolution and adapted to be revolved always at a constant speed.
  2. A lubricator comprising a reservoir, a cylinder block structure therein formed with alined pump cylinders, plungers operable in the cylinders, a pair of cams rigid together and relatively offset to depress the respective plungers therebeneath successively, and springs which constantly force 40 said plungers upwardly against said cams, whereby said cams will have a uniform speed of revolution and the action of one cam against the plungers will be counterbalanced and assisted by the action of the 45 plungers against the other cam.
  3. A lubricator comprising a reservoir, a cylinder block structure therein formed with alined pump cylinders, plungers operable in the cylinders, a plurality of revoluble 50 cams relatively immovable and adapted to be revolved always at a constant speed, said
- cams being in relative angular relation and having the same axis of revolution, and springs which normally tend to elevate the plungers and to keep them in constant contact with said cams, whereby any tendency toward intermittent acceleration of the speed of the cams caused by the spring actuated plungers is counteracted.
4. A lubricator comprising a reservoir, a cylinder block structure therein formed with alined pump cylinders, plungers operable in the cylinders, a shaft arranged above the plungers, and a plurality of cams keyed to the shaft in relatively angular relation to 60 permit of selective actuation of the plungers, one cam having a concave seat formed in one end to receive the opposing end of the adjacent end to thereby interlock the cams.
5. A lubricator comprising a reservoir, a series of alined cylinders provided with inlet ports communicating with said reservoir and outlet ports for communication with various bearings to be lubricated, 70 spring retracted plungers operable in the cylinders, and cams that are permanently fixed and relatively offset with respect to each other, one cam always operating to depress the plungers therebeneath while simultaneously the plungers beneath the other 75 cam are operating against the latter with a tendency to elevate it.
6. A lubricator comprising a reservoir, a cylinder block structure therein having alined cylinders provided with inlet and 80 outlet ports that communicate respectively with the reservoir and with suitable distributing pipes, spring retracted plungers operable in the cylinders, and relatively fixed and offset cams having the same axis 85 of revolution and always in contact with said plungers, one cam always operating with constantly increasing radii against one set of plungers to depress the latter while simultaneously the other set of plungers is 90 always being forced upwardly against the other cam at constantly decreasing radii of the latter, whereby said cams operate as auxiliaries one to the other in the depression of the plungers.

In testimony whereof I affix my signature.
BERNARD H. SKELLY.
